(57) **CLAIM**

The ornamental design for a folding chopping board, as shown and described.

DESCRIPTION

FIG. 1 is a top view of the folding chopping board with the legs folded.

FIG. 2 is a top view thereof with the legs extended.

FIG. 3 is a bottom view thereof with the legs folded.

FIG. 4 is a left side view thereof with the legs folded.

FIG. 5 is a right side view thereof with the legs folded.

FIG. 6 is a back view thereof with the legs folded.

FIG. 7 is a front view thereof with the legs folded.

FIG. 8 is a bottom view thereof with the legs unfolded.

FIG. 9 is a back view thereof with the legs unfolded.

FIG. 10 is a front view thereof with the legs unfolded.

FIG. 11 is a left side view thereof with the legs unfolded, and top surface sloping down to the front.

FIG. 12 is a right side view thereof with the legs unfolded, and the top surface sloping to the front; and,

FIG. 13 is a perspective view thereof with the legs unfolded with the front left leg in the foreground.
